UNITED STATES PATENT OFFICE.

EDGAR ROUSE SUTCLIFFE, OF LEIGH, ENGLAND.

MACHINE FOR COMPRESSING OR BRIQUETTING COAL OR OTHER MATERIAL.

Application filed December 22, 1923. Serial No. 682,266.

To all whom it may concern:

Be it known that I, EDGAR ROUSE SUTCLIFFE, a subject of the King of Great Britain and Ireland, residing at Leigh, Lancashire, England, have invented certain new and useful Improvements in Machines for Compressing or Briquetting Coal or Other Material, of which the following is a specification.

10 This invention relates to machines for compressing or briquetting coal or other material, and for other purposes to which rolls operating under pressure are applicable.

15 The invention especially relates to machines of the type in which open cavities are formed on the peripheries of a pair of rolls rotating at the same peripheral speed, and in which the cavities in the respective rolls come successively into register, so that on 20 material capable of being consolidated by pressure being fed into position between the rolls, briquettes or blocks are produced by compression of the material within the cavities, and are discharged at that side of the 25 rolls opposite to that at which the material is fed. The invention further relates to that class of machine of the type described in which rolls are respectively supported in 30 housings upon pairs of parallel tension elements in such manner as to be relatively movable thereon in the longitudinal direction, so that they may be applied one upon the other with adjustable pressure.

35 It is among the objects of the invention to apply high pressure between the rolls with a view to ensure effective consolidation of material not easily consolidated by pressure, to secure high efficiency and output, and generally to construct a machine that is effective in operation.

40 The invention has further for its objects to effect consolidation of coal and other similar solid carbonaceous substances without a binder by the reduction of the coal or 45 other carbonaceous substance to a condition of fineness before compression, and to render material in this finely divided condition more suitable for consolidation, so as thus to produce blocks or briquettes that are hard 50 and tough, from which de-gasified or carbonized fuel may be so produced. With reference to these objects, the invention may be employed in the production of fuel according to methods, the subject-matter of

prior patents granted to me No. 1,267,711 of 55 1918, No. 1,261,645 of 1918 and No. 1,283,354 of 1918.

According to the invention the housing of each roll, which is required to have movement in the longitudinal direction of the 60 parallel tension elements, is pivotally connected to a link or links pivoted axially with reference to the shaft from which the roll is driven. Where necessary, means may be provided to accommodate the movement 65 of the housing about the said shaft and with reference to the tension elements.

The invention further comprises means whereby the driven gear wheel of each roll is maintained in engagement with the driving gear wheel through which the drive is transmitted, even when the rolls separate as the material is pressed between them.

Pressure is advantageously applied between the respective rolls of a pair in known manner by means of a hydraulic ram or rams. For this purpose, according to the invention, the parallel tension elements on each side serve to connect the housing of the lower roll with a cross-head above the housing of 80 the upper roll. The ram or rams act between the top of the housing of the upper roll and the cross-head, and thus tension is imposed upon the tension elements, by which the rolls may be subjected to a pre-determined pressure.

The invention further comprises also the constructional features which are herein-after described.

A construction of roll machine according 90 to the invention is illustrated, by way of example, in the accompanying drawings in which—

Figure 1 is a side elevation of the rolling machine.

Figure 2 is an end elevation corresponding to Figure 1, and

Figure 3 is a corresponding plan.

In carrying the invention into effect according to the construction illustrated in 100 the drawings, I provide a pair of rolls a a' with cylindrical peripheries of the same diameter in rolling contact, upon which cavities a^2 a^3 are formed, advantageously at determined and equal distances apart, and the 105 rolls are geared in a manner such as herein-after described, so as to rotate at the same peripheral speed, and so that the respective

cavities a^2 a^3 on their peripheries successively come into register on the rotation of the rolls, whereby the material to be operated upon may be compressed within the respective pairs of cavities a^2 a^3 in register, and thus blocks or briquettes produced of a shape corresponding to the cavities. The cavities may have an oblong shape at the periphery of the rolls, and may be disposed across the 10 cylindrical face of the rolls parallel with the axis of the rolls. The sectional shape of the cavities in transverse planes is curvilinear, so that thus blocks or briquettes may be produced similar to so-called "ovoid" briquettes.

The rolls a a^1 may be so disposed that the plane passing through their axes lies at an angle such at 45° to the horizontal. The lower roll a^1 will thus lie in front of the upper roll a , and the material to be pressed, agglomerated, or consolidated may be fed into position between the rolls above the lower roll. The material may be fed by a "jigger" feed, or otherwise, so that the content of air within the finely divided material may be very substantially reduced, as described in the specification of a prior patent granted to me No. 1,283,354 of 1918. On the other side of the pair of rolls and beneath the upper roll a , means are advantageously provided to guide, and to convey away, the blocks or briquettes upon their production and discharge.

The rolls a a^1 have their cylindrical peripheries of a width to accommodate the cavities a^2 a^3 , and are mounted upon shafts a^4 a^5 that extend on each side of the rolls. The ends of the shafts a^4 a^5 are carried in housings b b^1 disposed on each side of the 40 rolls a a^1 , and the housings for the upper and lower rolls on the respective sides are connected together by means of tension bolts c that are parallel and that are disposed parallel with the plane passing through the 45 axes of the pair of rolls. The lower housing b^1 at each side consists of a block adapted at the upper part for the reception of the lower part b^2 of the bearing in which the shaft a^5 is supported in the housing, and the 50 top part b^3 of the bearing is held in position by means of a cap b^4 bolted at each side to the block. Similarly the housing b for the upper roll a at each side consists of a block adapted at the lower part for the reception of the top part b^5 of the bearing in which the shaft a^4 of the upper roll is supported in the housing; the lower part b^6 of the bearing being also retained by means of a cap b^7 , on the under-side of the block, which is 55 bolted to the block at each side. The tension bolts c are provided at the lower ends with nuts or collars c^2 , and pass through parallel holes in the blocks constituting the upper and lower housings b b^1 and extend through parallel holes in a cross-head d

mounted immediately above the upper block or housing b and at their upper ends are provided with nuts c^1 by which the bolts c may be secured to the cross-head. The cross-head d at each side of the rolls may be formed or provided with a hydraulic cylinder d^1 having its axis disposed in the plane passing through the axes of the rolls, and a ram e is mounted within the cylinder, whose lower end contacts with the top of the upper block or housing b . By such means a pre-determined hydraulic pressure may be maintained within the hydraulic cylinders on each side of the rolls whereby a very high pressure may be imposed between the peripheries of the rolls.

The lower housing or block b^1 at each side may be mounted upon a rod f carried in a position parallel with the axes of the rolls, upon the base frame g of the machine, so that thus it hinges thereon, in order to accommodate the movement of the upper roll, or the lower housing or block may be otherwise mounted for the same purpose. The upper housing or block b at each side is supported upon links h connected on the lower side of the housing and extending rearwardly and downwardly preferably in a position at right angles to the central plane of the connected housings b b^1 , and the links h are at their opposite lower ends conveniently carried upon the gear shaft i that may, according to the construction herein-after described, be supported from the base frame g of the machine in a position beneath and beside the upper blocks or housings b . Thus the weight of the rolls and the housings is taken in part by the rod f in front and in part by the gear shaft i at the rear.

The machine may be driven by belt and pulley, and the drive may be transmitted by a toothed pinion j and wheel k^1 to a counter-shaft k from which in turn the drive is transmitted by toothed pinion k^2 and wheel i^2 to the gear shaft i before referred to. The gear shaft i extends beneath and beside the upper housings or blocks b , and is supported at each side thereof within upstanding parts g^1 of the base frame of the machine. The drive is transmitted to the respective rolls from the gear shaft i by means of toothed pinions and wheels, one pinion i^2 gearing directly with a toothed wheel a^6 mounted upon the shaft a^4 while the other pinion i^3 gears with an intermediate toothed wheel l which in turn gears with the toothed wheel a^7 mounted upon the shaft a^5 of the lower roll a^1 . Thus the speed is reduced in three stages. By such an arrangement of the driving gear the toothed wheels a^6 a^7 on the roll shafts are maintained always in proper engagement with the driving gear notwithstanding the separation of the rolls as the material is pressed between them.

A machine such as described may be employed for the purpose of compressing the material to be eventually agglomerated or briquetted. For such a purpose the rolls 5 may be provided with plain cylindrical peripheries, or rollers provided with cavities in the manner and for the purposes described may be employed for pressing blocks or briquettes, which may be crushed or reduced 10 again into material suitable for final compression into blocks or briquettes that are hard and tough. When using for this purpose rolls having plain cylindrical peripheries, the material to be eventually agglomerated or briquetted may be positively fed 15 into and through the space between the pair of rolls, which may be maintained at a determined slight distance apart against the pressure to which the material is subjected 20 in passing between the rolls. Again when blocks, briquettes or consolidated masses are produced, to be again reduced and repressed, a pair of rolls may be employed for crushing or reducing the first consolidated 25 masses, and these rolls may be provided with irregular peripheries by which the consolidated masses may be crushed or reduced on passage between the rolls.

Any other means than specifically before 30 described may be employed to apply pressure between the rolls, that is to say instead of a hydraulic ram, spiral springs may be provided adapted to apply pressure at the ends of the shafts on which the rolls are 35 mounted, and mechanical means provided to regulate the degree of pressure to be applied. It will, however, be understood that where relatively great pressures are required such for example as from 2 to 10 tons per 40 square inch, it is preferred to employ hydraulic rams in the manner described.

The means provided to guide and convey away the blocks or briquettes as they are formed by the rolls may be of any suitable 45 kind. Thus, a travelling belt or conveyor or a chute may be provided upon which or into which the blocks or briquettes are received.

A machine of comparatively small size 50 may be constructed to give an output of from 2½ to 5 tons per hour or more, according to the speed of operation. For greater output the diameter of the rolls may advantageously be increased, or the rolls may 55 be provided with a plurality of peripheral series of mould spaces or recesses for use in the manner described.

A machine such as described, it will be understood, may be used as a grinding mill 60 operating under heavy load, the rolls being provided of a form suitable for this purpose, it being understood that the method and means of supporting the rolls and of transmitting movement to the rolls will be the same as hereinbefore described. The inven-

tion is thus broadly applicable for purposes to which rolls operating under pressure are applicable.

It will furthermore be understood that means are provided for effecting the lubrication of the bearings, accessible from in front of the machine as indicated at *m*.

I claim:

1. A compressing or briquetting machine, comprising in combination a pair of co-acting rolls, housings supporting the said rolls, means for applying pressure between the said rolls, tension elements upon which the said housings together with the said rolls are relatively movable and through 75 which pressure is applied, driving gear by which both rolls of the said pair are driven, and means comprising links for permitting in the operation of the machine the relative movement of the said housings together with 80 their rolls, substantially as described.

2. A compressing or briquetting machine, comprising in combination a pair of co-acting rolls, housings supporting the said rolls, means for applying pressure between 90 the said rolls, tension elements upon which the said housings together with the said rolls are relatively movable and through which pressure is applied, driving gear by 95 which both rolls of the said pair are driven, and means for permitting in the operation of the machine the relative movement of the said housings together with their rolls comprising links pivotally connected at one end to the housings of one of the said rolls, and at the other pivotally mounted upon the axis of a shaft from which the said roll is driven, substantially as described.

3. A compressing or briquetting machine comprising in combination a pair of co-acting rolls disposed with the plane passing through their axes at an angle to the horizontal such as to dispose one roll in front of and beneath the other, means for applying pressure between the said rolls, housings 105 for the said rolls, tension elements upon which the said housings together with the said rolls are relatively movable, driving gear by which the rolls of the said pair are driven, means for the support and pivotal connection of the housings of the lower roll to a base plate, and means permitting in the operation of the machine the relative movement of the upper roll and lower roll 110 comprising links pivotally connected to and supporting the housings of the upper roll, substantially as described.

4. A compressing or briquetting machine comprising in combination a pair of co-acting rolls, housings supporting the said rolls, means for applying pressure between the said rolls, tension elements upon which the said housings together with the said rolls are relatively movable and through which 125 pressure is applied, driving gear by which 130

both rolls of the said pair are driven, the said gear comprising a gear shaft, a pinion thereon, said pinion gearing with a toothed wheel on one of the roll shafts, a second pinion on the said gear shaft gearing through an intermediate toothed wheel with a toothed wheel mounted upon the other roll shaft, and means for permitting in the

operation of the machine the relative movement of the said housings together with their rolls comprising links pivotally connected at one end to the housings of one of the said rolls and at the other pivotally mounted on the axis of the said gear shaft, substantially as described.

EDGAR ROUSE SUTCLIFFE.
